R. R. FOUTE.
AUTOMATIC STOP FOR PHONOGRAHS.
FILED MAR. 7, 1922.

Inventor:
Raymond R. Foute
By L. L. Clegg Atty.

UNITED STATES PATENT OFFICE.

RAYMOND R. FOUTE, OF CHICAGO, ILLINOIS.

AUTOMATIC STOP FOR PHONOGRAHS.

Application filed March 7, 1922. Serial No. 541,762.

To all whom it may concern:

Be it known that I, RAYMOND R. FOUTE, citizen of the United States, residing at Chicago, in the county of Cook and State 5 of Illinois, have invented a certain new and useful Improvement in Automatic Stops for Phonographs, of which the following is a full, clear, concise, and exact description.

My invention relates to those phonographs which employ each a disc record supporting turn table and a tone arm mounted at one end upon one side of the turn table axis to swing over the turn table and carrying at its other end a transmitter that is 10 provided with a stylus which is engageable with record grooves to swing the tone arm and propagate sound therethrough.

The invention has for its object the provision of improved mechanism for stopping 20 the turn table and set into operation by the tone arm at the conclusion of a record. In practicing my invention I employ a turn table stopping member, a pivoted mounting for this member that includes a tooth 25 thereon which projects toward the axis of this mounting, a pivoted detent having a nose between the tooth and axis of said mounting and which is engageable with said tooth to position said mounting to hold the 30 turn table stopping member ineffective, there being an abutment against which the detent is held when in released position, and spring means operating upon said mounting and the detent and serving to press the 35 detent nose away from the axis of said mounting and also serving to turn the said mounting to make said turn table stopping member effective when the detent is released, said detent and tone arm being engageable 40 upon the inward record effected movement of the tone arm in a direction to release the detent to render the turn table stopping member effective, the portions of the tone arm and detent structures that are engageable being relatively adjustable to determine 45 the place in the inward record effected movement of the tone arm at which the detent is to be released.

My invention has been embodied in that 50 class of phonographs employing turn tables that are provided with rims and braking members that are applicable to said rims. A phonograph of this class, in accordance with my invention, has its braking member 55 mounted upon the pivoted mounting of my invention.

I will explain my invention more fully by reference to the accompanying drawing in which Fig. 1 illustrates the preferred embodiment thereof in connection with a 60 phonograph whose turn table has a rim and a braking member engageable with said rim, parts being broken away to reveal characteristics of construction, the braking member being unapplied to the turn table 65 rim; Fig. 2 is a view of part of the structure shown in Fig. 1 illustrating the brake member applied to the turn table rim; Fig. 3 is a sectional view on line 3—3 of Fig. 2; and Fig. 4 is a sectional view on line 70 4—4 of Fig. 2.

Like parts are indicated by similar characters of reference throughout the different figures.

An upright shaft or spindle 2 extends 75 through the mounting board and is turned by the motor at a set speed maintained substantially constant by any usual or suitable governor. The record supporting turn table 4 is carried upon the spindle 2 and rotates 80 therewith. This turn table supports a disc record 5 having recording grooves therein which commence at the periphery of the disc and terminate at the inner portion of the record. The tone arm 6 is mounted at 85 one end upon one side of the turn table axis to swing over the turn table 4. This tone arm supports a transmitting sound box 7 which carries a stylus 8 that is engageable with the grooves in the record 5 whereby 90 the tone arm is swung toward the center of the record as such record is being reproduced while the sound transmitter is propagating sound through the tone arm.

The rim 9 of the turn table constitutes 95 one element of a braking mechanism, the complementary braking member being preferably in the form of a cylindrical pad 10. The braking member 10 is supported upon a mounting 11 which is pivoted at 12 upon 100 a mounting plate 13 that is secured in place upon the mounting board of the phonograph by means of screws 14. The pivoted mounting has a tooth 15 formed thereon which projects toward the axis of the brake 105 member mounting 11. This mounting is provided with a surface at 16 on one side of the tooth, this surface being substantially concentric with the axis of the mounting and constituting an abutment serving the 110 purpose hereinafter to be stated. The portion of the mounting 11 upon the other side

of the tooth and adjacent thereto is spaced apart from the axis of the mounting a radial distance substantially equal to the radial distance of the surface 16. A detent 17 is pivoted at 18 upon the mounting board. This detent has a nose 19 that is between the tooth and the axis of the brake member mounting 11, this nose being engageable with the side of the tooth that is nearest the pivot 18 to hold the mounting in a position in which the brake is released from engagement with the turn table rim. When this nose is disengaged from this tooth the mounting 11 may be adjusted to bring the brake member 10 in engagement with the rim of the turn table to stop its rotation.

A coiled spring 20 connects the mounting 11 and the detent 17 and serves to press the detent nose away from the axis of the brake member mounting and also serves to turn the brake member mounting in a direction to apply the brake member to the turn table rim when the detent is released, said detent and tone arm being in engagement upon the inward record effected movement of the tone arm at the conclusion of a record in a direction to oppose the action of the spring to move the nose of the detent out of engagement with the tooth 15 upon the brake member mounting to permit the spring 20 to turn the mounting 11 to apply the brake member 10 against the turn table rim. The means for engaging the tone arm and the detent desirably resides in a post 21 carried by and depending from the tone arm and an arm 22 hinged at 23 to the detent and adapted to be held in positions to which it is adjusted by means of a spring washer 24 and a disc of friction producing material 25 such as felt or paper, a screw 26 regulating the friction which occurs at the joint between the arm 22 and the detent. In order to adjust the turn table stopping mechanism the stylus is swung inwardly a half inch or so beyond the termination of the record and is then swung back with the stylus upon the concluding line of the record whereafter the arm 22 is swung until it engages the post 21. After this adjustment has been effected the phonograph may be started, the tone arm being now adjusted to have its stylus 8 at the commencement of the record. When the stylus again reaches the concluding line of the record the stop 21 will impinge upon the arm 22 to release the detent from the tooth 15 whereupon the spring 20 will swing the brake member mounting 11 in a direction to apply the brake member 10 to the rim of the turn table. The surface 16 holds the detent nose stationary when released and while the mechanism is being set.

The advantages of the stopping mechanism of my invention will be readily un-

derstood by those skilled in the art and while the construction herein shown has been adapted to a phonograph employing braking mechanism the invention is not to be thus limited.

While I have herein shown and particularly described the preferred embodiment of my invention I do not wish to be limited to the precise details of construction shown as changes may readily be made without departing from the spirit of my invention but having thus described my invention I claim as new and desire to secure by Letters Patent the following:

1. A phonograph including a disc record 80 supporting turn table having a depending rim; a tone arm mounted at one end upon one side of the turn table axis to swing over the turn table and carrying at its other end a transmitter that is provided with a stylus 85 which is engageable with record grooves to swing the tone arm and propagate sound therethrough; braking mechanism for checking the rotation of said turn table and having said turn table rim as one of its elements, 90 the complemental element of the braking mechanism including a brake member applicable to said turn table rim, and a pivoted mounting for this brake member that includes a tooth thereon which projects toward the axis of this brake member mounting and which mounting is provided with a surface on one side of said tooth that is substantially concentric with the axis of the 95 mounting, the portion of the mounting upon 100 the other side of said tooth and adjacent thereto being spaced apart from the axis of the mounting a radial distance substantially equal to the radial distance of said surface; a pivoted detent having a nose between the tooth and axis of the brake member mounting and which is engageable with said tooth upon the side thereof remote from the aforesaid surface that is substantially concentric with the axis of the brake member 105 mounting to hold the brake member out of engagement with the turn table rim and which nose is also engageable with this surface when the detent is released to permit the application of the brake member to the turn table rim, and a spring connecting the brake member mounting and the detent and serving to press the detent nose away from the axis of the brake member mounting and also serving to turn the brake member 110 mounting in a direction to apply the brake member to the turn table rim when the detent is released, said detent and tone arm 115 being engageable upon the inward record effected movement of the tone arm in a direction to oppose the action of said spring to move the nose of the detent out of engagement with the tooth upon the brake member mounting and permit application of the 120 brake member to the turn table rim by said 125 130

spring, the portions of the tone arm and
detent structures that are engageable being
relatively adjustable to determine the place
in the inward record effected movement of
5 the tone arm at which the detent is to be re-
leased.

2. A phonograph including a disc record
supporting turn table; a tone arm mounted
at one end upon one side of the turn table
10 axis to swing over the turn table and carrying
at its other end a transmitter that is pro-
vided with a stylus which is engageable with
record grooves to swing the tone arm and
propagate sound therethrough; braking
15 mechanism for checking the rotation of said
turn table and having a brake member ap-
plicable to said turn table and a pivoted
mounting for this brake member that in-
cludes a tooth thereon which projects to
20 ward the axis of this brake member mount-
ing and which mounting is provided with a
surface on one side of said tooth that is
substantially concentric with the axis of the
mounting, the portion of the mounting upon
25 the other side of said tooth and adjacent
thereto being spaced apart from the axis of
the mounting a radial distance substantially
equal to the radial distance of said surface;
a pivoted detent having a nose between the
30 tooth and axis of the brake member mount-
ing and which is engageable with said tooth
upon the side thereof remote from the aforesaid
surface that is substantially concentric with
the axis of the brake member mount-
35 ing to hold the brake member out of engage-
ment with the turn table and which nose is
also engageable with this surface when the
detent is released to permit the application
of the brake member to the turn table; and
40 a spring connecting the brake member
mounting and the detent and serving to press
the detent nose away from the axis of the
brake member mounting and also serving to
turn the brake member mounting in a direc-
45 tion to apply the brake member to the turn
table when the detent is released, said detent
and tone arm being engageable upon the in-
ward record effected movement of the tone
arm in a direction to oppose the action of
50 said spring to move the nose of the detent
out of engagement with the tooth upon the
brake member mounting and permit applica-
tion of the brake member to the turn table
by said spring, the portions of the tone arm
55 and detent structures that are engageable
being relatively adjustable to determine the
place in the inward record effected move-
ment of the tone arm at which the detent is
to be released.

60 3. A phonograph including a disc record
supporting turn table having a depending
rim; a tone arm mounted at one end upon
one side of the turn table axis to swing over
the turn table and carrying at its other end
65 a transmitter that is provided with a stylus

which is engageable with record grooves
to swing the tone arm and propagate sound
therethrough; braking mechanism for
checking the rotation of said turn table and
having said turn table rim as one of its ele-
70 ments, the complemental element of the
braking mechanism including a brake mem-
ber applicable to said turn table rim, and a
pivoted mounting for this brake member
that includes a tooth thereon which pro-
75 jects toward the axis of this brake mem-
ber mounting and which mounting is pro-
vided with a surface on one side of said
tooth that is substantially concentric with
the axis of the mounting, the portion of
80 the mounting upon the other side of said
tooth and adjacent thereto being spaced
apart from the axis of the mounting a ra-
dial distance substantially equal to the ra-
dial distance of said surface; a pivoted de-
85 tent having a nose between the tooth and
axis of the brake member mounting and
which is engageable with said tooth upon
the side thereof remote from the aforesaid
surface that is substantially concentric with
90 the axis of the brake member mounting to
hold the brake member out of engagement
with the turn table rim and which nose is
also engageable with this surface when the
detent is released to permit the application
95 of the brake member to the turn table rim;
and spring means operating upon the brake
member mounting and the detent and serv-
ing to press the detent nose away from the
axis of the brake member mounting and also
100 serving to turn the brake member mounting
in a direction to apply the brake member to
the turn table rim when the detent is re-
leased, said detent and tone arm being en-
gageable upon the inward record effected
105 movement of the tone arm in a direction
to release the detent to permit application
of the brake member, the portions of the
tone arm and detent structures that are en-
gageable being relatively adjustable to de-
110 termine the place in the inward record ef-
fected movement of the tone arm at which
the detent is to be released.

4. A phonograph including a disc record
supporting turn table; a tone arm mounted
at one end upon one side of the turn table
axis to swing over the turn table and carrying
at its other end a transmitter that is pro-
vided with a stylus which is engageable
120 with record grooves to swing the tone arm
and propagate sound therethrough; braking
mechanism for checking the rotation of said
turn table and having a brake member appli-
cable to said turn table, and a pivoted
125 mounting for this brake member that in-
cludes a tooth thereon which projects to
ward the axis of this brake member mount-
ing and which mounting is provided with
a surface on one side of said tooth that is
130 substantially concentric with the axis of

the mounting, the portion of the mounting upon the other side of said tooth and adjacent thereto being spaced apart from the axis of the mounting a radial distance substantially equal to the radial distance of said surface; a pivoted detent having a nose between the tooth and axis of the brake member mounting and which is engageable with said tooth upon the side thereof remote 5 from the aforesaid surface that is substantially concentric with the axis of the brake member mounting to hold the brake member out of engagement with the turn table and which nose is also engageable with this surface 10 when the detent is released to permit the application of the brake member to the turn table; and spring means operating upon the brake member mounting and the detent and serving to press the detent nose 15 away from the axis of the brake member mounting and also serving to turn the brake member mounting in a direction to apply the brake member to the turn table when the detent is released, said detent and tone arm 20 being engageable upon the inward record effected movement of the tone arm in a direction to release the detent to permit application of the brake member, the portions 25 of the tone arm and detent structures that are engageable being relatively adjustable to determine the place in the inward record effected movement of the tone arm at which the detent is to be released.

5. A phonograph including a disc record 30 supporting turn table; a tone arm mounted at one end upon one side of the turn table axis to swing over the turn table and carrying at its other end a transmitter that is provided with a stylus which is engageable with record grooves to swing the tone arm and propagate sound therethrough; a turn 35 table stopping member; a pivoted mounting for this member that includes a tooth thereon which projects toward the axis of this mounting and which mounting is provided with a surface on one side of said tooth that is substantially concentric with the axis 40 of the mounting, the portion of the mounting upon the other side of said tooth and adjacent thereto being spaced apart from the axis of the mounting a radial distance substantially equal to the radial distance of 45 said surface; a pivoted detent having a nose between the tooth and axis of said mounting and which is engageable with said tooth upon the side thereof remote from the aforesaid surface that is substantially concentric with the axis of said mounting to hold the turn table stopping member ineffective and which nose is also engageable with this surface when the detent is released to make the turn 50 table stopping member effective; and spring means operating upon said mounting and the detent and serving to press the detent nose away from the axis of said mounting and also serving to turn the said mounting to make said turn table stopping member effective when the detent is released, said detent and tone arm being engageable upon the inward record effected movement of the tone arm in a direction to release the detent 55 to render the turn table stopping member effective, the portions of the tone arm and detent structures that are engageable being relatively adjustable to determine the place in the inward record effected movement of the tone arm at which the detent is to be released.

65 6. A phonograph including a disc record supporting turn table; a tone arm mounted at one end upon one side of the turn table axis to swing over the turn table and carry-

of said mounting and also serving to turn the said mounting to make said turn table stopping member effective when the detent is released, said detent and tone arm being engageable upon the inward record effected 70 movement of the tone arm in a direction to oppose the action of said spring to move the nose of the detent out of engagement with the tooth upon said mounting to render the turn table stopping member effective, 75 the portions of the tone arm and detent structures that are engageable being relatively adjustable to determine the place in the inward record effected movement of the tone arm at which the detent is to be released.

6. A phonograph including a disc record supporting turn table; a tone arm mounted at one end upon one side of the turn table axis to swing over the turn table and carrying at its other end a transmitter that is provided with a stylus which is engageable with record grooves to swing the tone arm and propagate sound therethrough; a turn table stopping member; a pivoted mounting for this member that includes a tooth thereon which projects toward the axis of this mounting and which mounting is provided with a surface on one side of said tooth that is substantially concentric with the axis 95 of the mounting, the portion of the mounting upon the other side of said tooth and adjacent thereto being spaced apart from the axis of the mounting a radial distance substantially equal to the radial distance of 100 said surface; a pivoted detent having a nose between the tooth and axis of said mounting and which is engageable with said tooth upon the side thereof remote from the aforesaid surface that is substantially concentric with the axis 105 of said mounting to hold the turn table stopping member ineffective and which nose is also engageable with this surface when the detent is released to make the turn table stopping member effective; and spring means operating upon said mounting and the detent and serving to press the detent nose away from the axis of said mounting and also serving to turn the said mounting to make said turn table stopping member effective when the detent is released, said detent and tone arm being engageable upon the inward record effected movement of the tone arm in a direction to release the detent 110 to render the turn table stopping member effective, the portions of the tone arm and detent structures that are engageable being relatively adjustable to determine the place in the inward record effected movement of the tone arm at which the detent is to be released.

7. A phonograph including a disc record supporting turn table; a tone arm mounted at one end upon one side of the turn table axis to swing over the turn table and carry-

ing at its other end a transmitter that is provided with a stylus which is engageable with record grooves to swing the tone arm and propagate sound therethrough; braking mechanism for checking the rotation of said turn table and having a brake member applicable to said turn table, and a pivoted mounting for this brake member that includes a tooth thereon which projects toward the axis of this brake member mounting and which mounting is provided with a surface on one side of said tooth that is substantially concentric with the axis of the mounting; a pivoted detent having a nose between the tooth and axis and axis of the brake member mounting and which is engageable with said tooth upon the side thereof remote from the aforesaid surface that is substantially concentric with the axis of the brake member mounting to hold the brake member out of engagement with the turn table and which nose is also engageable with this surface when the detent is released to permit the application of the brake member to the turn table; and spring means operating upon the brake member mounting and the detent and serving to press the detent nose away from the axis of the brake member mounting and also serving to turn the brake member mounting in a direction to apply the brake member to the turn table when the detent is released, said detent and tone arm being engageable upon the inward record effected movement of the tone arm in a direction to release the detent to permit application of the brake member, the portions of the tone arm and detent structures that are engageable being relatively adjustable to determine the place in the inward record effected movement of the tone arm at which the detent is to be released.

8. A phonograph including a disc record supporting turn table; a tone arm mounted at one end upon one side of the turn table axis to swing over the turn table and carrying at its other end a transmitter that is provided with a stylus which is engageable with record grooves to swing the tone arm and propagate sound therethrough; a turn table stopping member; a pivoted mounting for this member that includes a tooth thereon which projects toward the axis of this mounting and which mounting is provided with a surface on one side of said tooth that is substantially concentric with the axis of the mounting; a pivoted detent having a nose between the tooth and axis of said mounting and which is engageable with said tooth upon the side thereof remote from the aforesaid surface that is substantially concentric with the axis of said mounting to hold the turn table stopping member ineffective and which nose is also engageable with this surface when the detent is released to make the

turn table stopping member effective; and spring means operating upon said mounting and the detent and serving to press the detent nose away from the axis of said mounting and also serving to turn the said mounting to make said turn table stopping member effective when the detent is released, said detent and tone arm being engageable upon the inward record effected movement of the tone arm in a direction to release the detent to render the turn table stopping member effective, the portions of the tone arm and detent structures that are engageable being relatively adjustable to determine the place in the inward record effected movement of the tone arm at which the detent is to be released.

9. A phonograph including a disc record supporting turn table; a tone arm mounted at one end upon one side of the turn table axis to swing over the turn table and carrying at its other end a transmitter that is provided with a stylus which is engageable with record grooves to swing the tone arm and propagate sound therethrough; braking mechanism for checking the rotation of said turn table and having a brake member applicable to said turn table, and a pivoted mounting for this brake member that includes a tooth thereon which projects toward the axis of this brake member mounting; a pivoted detent having a nose between the tooth and axis of the brake member mounting and which is engageable with said tooth to position the brake member mounting to hold the brake member out of engagement with the turn table, there being an abutment against which the detent is held when in released position; and spring means operating upon the brake member mounting and the detent and serving to press the detent nose away from the axis of the brake member mounting and also serving to turn the brake member mounting in a direction to apply the brake member to the turn table when the detent is released, said detent and tone arm being engageable upon the inward record effected movement of the tone arm in a direction to release the detent to permit application of the brake member, the portions of the tone arm and detent structures that are engageable being relatively adjustable to determine the place in the inward record effected movement of the tone arm at which the detent is to be released.

10. A phonograph including a disc record supporting turn table; a tone arm mounted at one end upon one side of the turn table axis to swing over the turn table and carrying at its other end a transmitter that is provided with a stylus which is engageable with record grooves to swing the tone arm and propagate sound therethrough; a turn table stopping member; a pivoted mounting for this member that includes a tooth thereon

which projects toward the axis of this mounting; a pivoted detent having a nose between the tooth and axis of said mounting and which is engageable with said tooth to position said mounting to hold the turn table stopping member ineffective, there being an abutment against which the detent is held when in released position; and spring means operating upon said mounting and the detent and serving to press the detent nose away from the axis of said mounting and also serving to turn the said mounting to make said turn table stopping member effective when the detent is released, said

detent and tone arm being engageable upon the inward record effected movement of the tone arm in a direction to release the detent to render the turn table stopping member effective, the portions of the tone arm and detent structures that are engageable being relatively adjustable to determine the place in the inward record effected movement of the tone arm at which the detent is to be released.

In witness whereof, I hereunto subscribe my name this 18th day of February, A. D. 1922.

RAYMOND R. FOUTE.
